EDWARD C. MARQUA, OF KANSAS CITY, MISSOURI.

COLLAPSIBLE FORM FOR CONCRETE CONSTRUCTION-WORK.

1,285,295.

Specification of Letters Patent. Patented Nov. 19, 1918.

Application filed September 27, 1917, Serial No. 193,428. Renewed September 21, 1918. Serial No. 255,182.

To all whom it may concern:

Be it known that I, EDWARD C. MARQUA, a citizen of the United States, residing at Kansas City, in the county of Jackson and 5 State of Missouri, have invented certain new and useful Improvements in Collapsible Forms for Concrete Construction-Work; and I do declare the following to be a full, clear, and exact description of the invention, 10 such as will enable others skilled in the art to which it appertains to make and use the same, reference being had to the accompanying drawings, and to the letters and figures of reference marked thereon, which 15 form a part of this specification.

My invention relates to collapsible forms for concrete construction work, and more particularly to dome forms used in the making of concrete floors or the like, wherein 20 the forms are arranged along supporting soffits to form a mold for the floor and supporting joists; the principal object of the invention being to provide an improved form of this character provided with easily ad- 25 justable means for retaining the collapsible sections in functional relation while in use, and which may be easily and quickly re- moved to permit collapsing of the parts when it is desired to remove the form from 30 the finished work.

In accomplishing this object, I have pro- 35 vided improved details of structure the pre-ferred forms of which are illustrated in the accompanying drawings, wherein:

Figure I is a perspective view of a concrete floor in the course of construction, particu-larly illustrating the arrangement of the dome on a supporting structure to form the floor and joist mold.

Fig. II is a transverse section of a portion of a floor showing one of the forms locked in functional position, and an adjacent dome collapsed to permit its removal from the floor.

Fig. III is a detail perspective view of one of the dome forms, parts of which are broken away for better illustrating a tie member.

Fig. IV is a longitudinal vertical section of a portion of a form.

Referring more in detail to the drawings:

1 designates a dome constructed according to the present invention, which in its pre-ferred form consists of opposite paired side sections 2—2', comprising top plates 3—3', side members 4—4' and transverse dia-phragms 5 which are removably mounted

within the dome and spaced from the ends thereof to support the sections apart and to hold the side and top members in functional position; the top and side members of the 60 sections are here shown to each consist of a single board, although we do not wish to be limited to this detail, as it is apparent that either the top or the sides may be made up of several separate pieces, and that the pieces 65 of each top and side member may be rigidly and permanently connected by transverse battens 6—7 adjacent the opposite ends of the sections. The battens 6 not only serve to stiffen the body members to which they are 70 connected, but also serve to carry hinges 8 whereby the top and side members are con- 75 nected.

The preferred arrangement of the hinged parts is that wherein the edges of the top 75 members 3—3' overlie and are supported by the upper edges of the side members 4—4', and the arrangement being further such as that when the members are extended in functional position, the sides 4—4' will extend 80 at a slight obtuse angle to each other to taper the floor beam and brace the dome members against collapse.

As the widths of floor arches vary, we adapt the dome for such varying widths by 85 providing inserts 9 that are adapted to fill in between the spaced edges of the top plates 3—3' and which are of the same thickness as said top in order to form a smooth upper surface thereacross and obviate unevenness 90 in the tops of the arches and thickness of the slabs. These inserts are adapted for support on the tops of the diaphragms 5, and their width may be varied according to the space desired between the floor beams. 95

In order to rigidly support and space the paired side sections of the dome, when the latter is in use, we provide the interior trans-verse diaphragms 5, which are adapted for abutting against opposite sides 3—3' and 100 for seating on shoulders 10 on the inner edges of the side battens 7. The ends of the diaphragms are inclined to correspond with the side faces of the side members and fit closely and snugly thereagainst when the 105 diaphragms are set, and are held in place by tie members 12; each tie member comprising two lengths of spring wire, twisted to-gether at their centers as at 13, so as to leave upper and lower strands 14—15 diverging 110 in opposite directions from the twisted por-tion.

Each of the wires is provided at its ends with out-turned hook portions 16, and the hooks of the upper strand are adapted to seat in downwardly opening sockets 17-17' (Fig. II) in the top plates at the outer edges thereof, and the hooks on the lower strands are adapted to seat in sockets 18-18' opening upwardly from the shoulders 10 on the batten 7; the sockets being so located that when the diaphragm and tie members are in place, the latter serve to retain the collapsible form parts in functional relation and also hold the diaphragms on the batten shoulders to prevent any collapse of the dome.

I also provide for tightening the tie members 12 should they become lengthened by use, by inserting wedge blocks 19 between the twisted portions 13 and the adjacent diaphragms to press the wires outwardly and draw the sides of the dome tightly against the ends of the diaphragms, and the latter against the battens 7.

When it is desired to collapse the parts, the wedge blocks are first removed, and the arms of the tie members being yieldable, are sprung inwardly to unseat the hooked ends from the sockets and the ties removed from the dome. The diaphragms may then be lifted from the shouldered battens to allow the side sections to be closed together and removed from the work.

In order to give a clear understanding of the purpose and use of the dome I have shown the same with supporting soffits and part of a floor slab, 20 designating the supporting studs, 21 the temporary form beams and 22 soffit boards that are carried by the beams and in turn support the domes and form the bottoms of the form for the concrete floor beams.

In assembling the domes, the latter are set up by opening the side and top apart and the diaphragms 5 seated between the sides 4-4' on the shoulders 10 of the battens 7 so that the sides are extended and held in position by abutment of the ends of the diaphragms against the inner faces thereof, and the tie members are placed in position by springing the ends together so that the hooked ends may seat in the sockets provided adjacent the outer edges of the diaphragms in the top sections and shoulders, to hold the parts tightly together. The inserts 9 are then placed between the edges of the top members and supported by the diaphragms. The domes are then placed on the soffit boards and bridge the space therebetween, the lower edge of the side members 4-4' resting on the tops of the soffit boards adjacent the edges thereof, so that not only is the space between adjacent soffit boards covered by the arch of the domes, but there is space left between the side members of adjacent domes within which the floor beams

23 of the floor slab 24 is formed when the concrete is poured, the domes being arranged on the soffit boards in longitudinal alinement across the space to be floored so that continuous arches and floor beams may be 70 formed.

With the domes arranged in this manner, the concrete is poured therebetween to form the beams and thereover to a desired depth to form the slab. When the end beams have 75 been formed about and over the domes, and the concrete is set sufficiently to permit the domes to be removed, the body sections 2-2' are separated by first removing the tie members 12 as previously described, and removing the diaphragms 5 so that there is no support for the hinged top members and inserts that would prevent the inward collapse of the sides. The top members are then pulled downwardly on their hinges to separate the 85 same from the bottom of the slab and the sides 4-4' are then drawn away from the sides of the floor beam, so that the mold members may be removed from the slab and from the soffit without disturbing the soffit. 90

By constructing the domes in this manner, and by providing diaphragms and tie members of various standard lengths it is apparent that the same dome members may be used to construct different floors wherein 95 the beams are spaced either close or farther apart as is desired.

It is further apparent that the yieldable tie members provide for a quick assembly or collapse of the parts, are light and substantial, and occupy a small amount of space when stored with the collapsed forms.

Having thus described my invention, what I claim as new therein, and desire to secure by Letters Patent is:

1. In a dome for concrete structures comprising opposite side members, battens fixed in paired relation to said side members, diaphragms supported at their opposite ends between the side members and removable tie members extending between the side members to retain the diaphragms and side members in functional relation.

2. In a dome for concrete structures comprising paired side and top members, battens fixed to the inner faces of the side members in paired relation and having upwardly facing shoulders thereon, diaphragms extending between the side members and seated at their opposite ends on said shoulders and supporting the top members, and tie members removably attached to the opposite side members to retain the parts in functional relation.

3. In a dome for concrete structures comprising paired side and top members, battens fixed to the inner faces of the side members in paired relation and having upwardly facing shoulders provided with upwardly opening sockets, diaphragms extending be-

tween the side members and removably seated at their opposite ends on said shoulders to abut the side and support the top members, and tie members extending between the side members having end hooks thereon yieldably seated in said sockets to retain the diaphragms in functional position and support the top and side members.

4. A dome for concrete structures comprising paired side members, top members hinged to the said side members and having downwardly opening sockets adjacent their hinged edges, battens fixed to the inner faces of the side members in paired relation and having upwardly facing shoulders thereon provided with upwardly opening sockets, diaphragms extending between the side members and seated at their opposite ends on said shoulders to abut the side and support the top members, and tie members extended between the side members, adjacent the diaphragms and comprising hooked ends removably seated in said sockets in the top members and on the shoulders at opposite sides of the dome, to retain the diaphragms on the shoulders and the top and side members in functional position.

5. A dome for concrete structures comprising paired side members and top members hinged to the said side members and provided with downwardly opening sockets adjacent their hinged edges, battens fixed

to the inner faces of the side members in paired relation and having upwardly facing shoulders provided with upwardly opening sockets, diaphragms extending between the side members and seated at their opposite ends on said shoulders to abut the side and support the top members, and tie members extended between the side members comprising paired spring wires twisted together at their centers with the free ends diverging from each other in opposite directions, and having out-turned hooks at their ends yieldingly retained in paired sockets in the said shoulders and top members adjacent the outer faces of the diaphragms to retain the diaphragms in functional position on the shoulders.

6. In a dome of the character described comprising separate side sections having paired sockets and diaphragms extending between the side sections, tie members extended between the side sections, comprising paired spring wires twisted together at their centers with their free ends diverging from each other in opposite directions, and having out-turned hooks at their ends yieldingly seated in paired sockets at opposite sides of the sections for the purpose set forth.

In testimony whereof I affix my signature.

EDWARD C. MARQUA.
